HAND MILLER

Newman M. Marsilius, Bridgeport, Conn.

Application October 17, 1942, Serial No. 462,366

10 Claims. (Cl. 90—15)

1

This invention relates to new and useful improvements in milling machines and has particular relation to a hand type miller.

An object of the invention is to provide in a hand type milling machine an improved belt drive including means for maintaining predetermined center distances between driving pulleys as the cutter head is moved toward and from a piece of work.

Another object is to provide an improved counterbalancing means for a hand type milling machine whereby the cutter head will be maintained balanced in any position to which it may be shifted.

Other objects and advantages will become apparent from a consideration of the following detailed description taken in connection with the accompanying drawings wherein a satisfactory embodiment of the invention is shown. However it is to be understood that the invention is not limited to the details disclosed but includes all such variations and modifications as fall within the spirit of the invention and the scope of the appended claims.

In the drawings:

Fig. 1 is a side elevational view of the machine of the invention;

Fig. 2 is a front elevational view of said machine;

Fig. 3 is a view partly in horizontal section and partly in top plan view of the new machine, the view being taken as along the plane of the line 3—3 of Fig. 1;

Fig. 4 is an enlarged sectional view taken as along the line 4—4 of Fig. 3;

Fig. 5 is a sectional view taken as along the line 5—5 of Fig. 4; and

Fig. 6 is an enlarged sectional view taken as along the plane of the line 6—6 of Fig. 3.

Referring in detail to the drawings the machine of the invention includes an upright frame or base generally designated 10. At the lower rear side of the base is a coolant circulating pump and motor 11 and 12 connected in the usual manner (not shown) for the delivery of cutting fluid. Basically the machine of the invention includes a work support generally designated 13 and a cutter head generally designated 14, the details of the construction and operation of each of which will be described.

Support 13 includes an elongated basin-like part 15 open at its upper side and on its underside having a dove-tailed groove 16 receiving dove-tailed ways 17 on the upper side of a saddle 18 whereby the table is mounted for guided longi-

2

tudinal movements. Within the part 15 is a work holder 19 through which passes machine screws 20 also passing through the bottom wall of part 15 and into a rack 21. It is noted that the holder 19 has a longitudinally extending inverted T-shaped groove 22 opening through its upper side and which is to be used in mounting any work attaching fixture in the desired position on the holder.

10 A shaft 23 journaled in the saddle 18 has secured thereto a pinion 24 meshing with the teeth of the rack 21 and on the outer end of said shaft there is secured a handle or lever 25 for turning the shaft to rotate the pinion and feed the table

15 13 in the direction of its length along the ways 17. A lug 26 on the upper side of the saddle is disposed between adjustable screws 27 and 28 threaded through lugs 29 on the outer edge of table part 15. These screws are positioned to alternately engage the lug 26 as the support 13 is reciprocated and it will be understood that by adjusting the screws into the desired relation to one another the movements of the table may be limited as desired.

25 Saddle 18 in its under side has a dove-tailed groove 30 receiving dove-tailed ways 31 on the upper side of a vertically adjustable knee 32. Groove 30 and ways 31 are at right angles to the groove 16 and ways 17 and therefore it will be clear that by adjusting the saddle along its ways the table 13 is adjusted laterally. Adjustment of the saddle is affected by means of a feed screw 33 mounted against longitudinal movement by the part or knee 32 and threaded into a nut 34 fixed to the saddle. Screw 33 has an exposed end portion 35 shaped to receive a crank or like tool to be applied for the turning of the screw.

30 Knee 32 is mounted on vertical ways 36 on one side of the base 10. A heavy jack screw 37 is threaded into a knee elevating screw horn 38 and includes a reduced diameter portion 39 passing through a lug 40 rigid with the knee. The reduced portion is not threaded and is freely turnable in the lug 40 but the screw includes a shoulder 41 at the under side of said lug. Fixed to screw 37 is a bevelled gear 42 meshing with a similar gear 43 on the inner end of a shaft 44 passing through a wall of knee 32. Shaft 44 at its outer end is provided with a shaped portion 45 adapted for the reception of a crank or other tool to be applied for the turning of the shaft to rotate screw 37 and have it feed out of or into the horn 38 and thereby raise or lower the knee 32 on the ways 36.

35 45 A lock screw 46 is provided with a hand piece 47

and this screw is adapted to be set against the ways 31. As the screw is carried by the saddle 18 it will be clear that when the screw is tightened it will secure the saddle in the desired adjusted position along the ways. A similar screw 48, having a hand piece 49 is carried by the base 10 and is adapted to be tightened against the vertical ways 36 to lock the knee 32 in the desired position of vertical adjustment.

Cutter head 14 comprises a metal body 50 including a dove-tail shaped part 51 at its inner or rear side fitted in vertical ways 52 on the upper forward portion of the base. Body 50 mounts, for rotary movement, a spindle 53 extending beyond both sides of the body and at one end mounting a chuck 54 and at its other end having fixed thereon a stepped pulley 55. Mounted on and turnable about the spindle 53 intermediate the ends of body 50 is a toothed element or quadrant 56 having its teeth meshing with those of a rack 57 fixed to the forward face of the upper portion of the base, preferably in the ways 52.

A handle or lever 58 is fixed to the element 56 and extends to a convenient location for manual operation. By grasping the lever 58 and swinging it upwardly or downwardly the element 56 is turned about the spindle 53 as a pivot and its teeth meshing with those of the rack 57 the element rides on the rack and the entire cutter head 14 is moved upwardly or downwardly on the ways 52.

A part 59 fixed to the upper end of the base 10 includes a projection 60 through which passes a vertically disposed screw 61 fixed to the cutter head. Nuts 62 and 63 on said bolt at the upper and lower sides, respectively, of said projection are adjustable on the bolt and comprise stops to limit the vertical movements that may be imparted to the cutter head by the lever 58. It is to be understood that the nuts 62 and 63 are adjusted on the bolt 61 in accordance with any particular work to be performed.

The upper portion of body 50 is provided with a socket 64 and therebeyond is provided with a split 65. The socket receives an arm 66 the outer end of which supports a member 67 mounting an end bearing element 68 for the outer end of a milling cutter arbor 69. Member 67 is secured in the desired position of adjustment along the arm 66 by tightening of a screw 70. The inner end of the cutter spindle 69 is received in the chuck 64 and thus the cutter 71 is firmly mounted for rotary movement. Here it is noted that on tightening of screws 72 the split portion of the body 50 is drawn closed and the sides of the socket 64 grip or clamp the arm 66.

A rack 73 is pivotally connected with the lower side of the body 50 at 74 and passes into the base 10 through an opening 75. In the lower portion of the base below the cutter head is a weight 76 to which a vertically extending rack 77 is pivotally connected at 78. Between and meshing with the teeth of each of the racks 73 and 77 is a pinion 79 rotatably mounted by a shaft 80 supported by a bracket 81.

With this construction it will be clear that as the cutter head is moved on the ways 52 the rack 73 will be raised or lowered (depending on the movement imparted to the cutter head) and acting through the pinion 79 will cause a movement of the rack 77 in the reverse direction. The latter rack being connected therewith, the weight will be moved and serves to counter-balance the cutter head and retain it in the position to which it is moved by manipulation of lever 58.

It is here noted that the cutter head supports

the milling cutter 71 over the work support 13 and that the cutter head is mounted for vertical movement to carry the cutter toward and from said work support. Bolts 82 on the cutter head 5 are for the purpose of securing in place a housing or guard (not shown) for the pulley 55. In the ways 52 is a gib 83 adapted to be adjusted by manipulation of a screw 84 (see Fig. 2). The other ways of the machine are similarly equipped.

Stepped pulley 55, and consequently the spindle 53 to which said pulley is fixed, is driven from a motor 85 located in the lower rear portion of the base 10. The motor is mounted on a platform 86 pivoted at 87 and including a portion 88 carrying a pin 89 disposed in an inclined slot 90 in a part 91 adapted to be fed back and forth on a screw 92. As the part 91 is moved in one direction or the other the platform 86 will be rocked about the pivot 87 to raise and lower the motor 85.

From a stepped pulley 93 on the motor shaft 94 a belt 95 drives a stepped pulley 96 fixed on an intermediate shaft 97. The latter is rotatably mounted in a back 98 located between the upper and lower arms 99 and 100, respectively, of a support 101 carried by a back plate 102 secured to the rear upper portion of the base. Preferably support 101 is located in a horizontal line between the upper and lower ends of the ways 52.

Block 98 includes end flanges 103 and 104 overlying the lateral sides of the support arms 99 and 100 and serving to guide movements of the block between said arms by preventing lateral movement of the block. Beyond flange 104 the block includes a tubular portion 105 of reduced diameter the purpose of which will be set forth. Beyond flange 103 a stepped pulley 106 is fixed to the shaft 97 and a belt 107 drives the pulley 55, and thus the spindle 53, from the pulley 106.

Block 98 is slidable horizontally between the support arms 99 and 100 and rests on the latter. Thus shaft 97 is not fixed with respect to the support 101 and may move horizontally thereon to compensate for changes in the distance between the center of the spindle 53 and any fixed part of the support which changes result from movements of the cutter head on the ways 52.

However a simple means is provided to maintain a fixed center distance between spindle 53 and shaft 97. Such means includes a part 108 about the reduced portion 105 of block 98 and a means 109, comprising parts 110 and 111 clamped about a reduced portion 112 on the quadrant 56 (see Fig. 4). Parts 110 and 111 are connected at the upper side of the spindle by a screw 113 and at the lower side of the spindle by a reduced portion 114 of a member 115 passing through both parts.

At the rear side of part 111 member 115 includes a shoulder 116 bearing against said part 60 and at the front side of the part 110 the member 115 is threaded and receives a nut 117 which when tightened draws the shoulder 116 against part 111 and the nut is then permanently pinned in place thus securing parts 110 and 111 together. Member 115 also includes an internally threaded tubular portion 118.

A member 119 has a flattened end portion 120 secured by bolts 121 to the lower portion of part 108 and this member also includes a shank portion 122 threaded into the tubular portion 119 of the member 115. Thus the means comprising the part 108, the means 109 and the threadedly connected members 115 and 119 serves to connect the shaft 97 and the spindle 53 and to maintain them in fixed spaced relation.

Should it be desired to shift the belt 95 to different steps of the pulleys 93 and 96 the belt may be slackened by raising the motor 85 on proper manipulation of the screw 92. After the belt is shifted the screw is again manipulated to return the motor to position with the belt tightened. In like manner should it be desired to shift the belt 107 to different steps of the pulleys 55 and 106 a suitable tool is applied to the squared end 123 of the member 115 to rotate it and bring about a further telescoping of the members 115 and 119 drawing the block 98 forwardly on support 101 and slackening the belt 107.

After the belt has been shifted as desired the member 115 is rotated in the opposite direction to shift the block 98 backwardly on the support 101 to again tighten the belt. It will be understood that the screw 92 and the member 115 may be manipulated to bring about tightening of the respective belts should they become stretched in use.

Pulleys 106 and 55 are held on the shaft 97 and spindle 53 by nuts 124 and 125 respectively. For changes in the speed at which the spindle 53 is driven the mentioned nuts may be removed and the positions of the pulleys reversed, applying pulley 55 to shaft 97 and pulley 106 to spindle 53 after which the nuts are replaced. Preferably the nuts are knurled for ease of manipulation. With the disclosed construction the pulleys 55 and 106 may be readily replaced with other pulleys of desired ratio.

From the foregoing it will be seen that I have provided a simple and effective means for counter-balancing the cutter head 14 with the weight 76. In addition it will be seen that I have provided an effective belt drive from the motor 85 to the spindle 53 and have provided means whereby the shifting of the center of the spindle as the cutter head is moved vertically is compensated for so that there is no need to stretch the driving belt in order to effect a belt drive of the cutter spindle and yet have the cutter head shiftable vertically.

As the cutter head moves out of horizontal alignment with the shaft 97 (during use of the machine) and the center distance between the spindle 53 and the shaft 97 tends to increase the said shaft is moved horizontally forwardly. On reverse movement of the cutter head as the center distance tends to decrease between the spindle and shaft the latter is moved rearwardly on the support 101.

Thus as the cutter head is moved from horizontal alignment with the shaft 97 and moved back into such alignment the center distance between the spindle 53 and the shaft 97 remains constant, movement of said shaft compensating for any change of the distance between the center of the spindle and any fixed part of the shaft support, i. e. support 101. Therefore the belt drive of the spindle is effected from the motor 85 without imposing stretching strain on the belt but with the latter in any predetermined degree of tension.

Having thus set forth the nature of my invention, what I claim is:

1. In a hand type milling machine, a base, a cutter head, means mounting the cutter head on the base for vertical movements, means for moving the cutter head vertically, a spindle mounted for rotary movement by the cutter head, a motor on the base, a belt drive from the motor to the spindle comprising a shaft, pulleys fixed to the shaft, a belt driving one of the pulleys from the

motor, a belt driving the spindle from another of the pulleys, rigid means connecting the shaft and spindle and maintaining them in fixed spaced relation and adapted to impart movement from one to the other, and means mounting the shaft for movement by said rigid means to compensate for the shifting of the center of the spindle as the cutter head is moved vertically.

2. In a hand type milling machine, a base 10 having vertical ways, a cutter head mounted on said ways, a vertical rack fixed to said base, a toothed means pivotally mounted on said head and meshing with said rack, means for turning said toothed means on its pivot to have it ride said rack and move the head along the ways, a spindle mounted for rotary movement by said head, a motor on said base, a belt drive from the motor to said spindle comprising a shaft, pulleys fixed to said shaft, a belt driving one of said pulleys from said motor, a belt driving the spindle from another of said pulleys, rigid means connecting the shaft and spindle and maintaining them in fixed spaced relation and adapted to impart movement from one to the other, and means mounting said shaft for movement by said rigid means to compensate for the shifting of the center of the spindle as the cutter head is moved vertically on said ways.

3. In a hand type milling machine, a base, a cutter head, means mounting the cutter head on the base for vertical movements, means for moving the cutter head vertically, a spindle mounted for rotary movement by the cutter head, a motor on said base, a belt drive from the motor to the spindle comprising a shaft, pulleys fixed to said shaft, a belt driving one of said pulleys from the motor, a belt driving the spindle from another of said pulleys, rigid means connecting said shaft and spindle and maintaining them in fixed spaced relation comprising a pair of rigid parts relatively adjustable to vary the distance between the centers of the shaft and spindle and adapted to impart movement from one to the other, and means mounting said shaft for movement by said rigid means to compensate for the shifting of the center of said spindle as the cutter head is moved vertically.

4. In a hand type milling machine, a base, a cutter head, means mounting the cutter head on the base for vertical movements, means for moving the cutter head vertically, a spindle mounted for rotary movement by the cutter head, a motor on said base, a belt drive from the motor to the spindle comprising a shaft, pulleys fixed to said shaft, a belt driving one of said pulleys from the motor, a belt driving the spindle from another of the pulleys, rigid means connecting the shaft and spindle and maintaining them in fixed spaced relation comprising a pair of rigid parts screw threaded together for relative adjustment to vary the distance between the centers of the shaft and spindle and adapted to impart movement from one to the other, and means mounting said shaft for movement by said rigid means to compensate for shifting of the center of said spindle as the cutter head is moved vertically.

5. In a hand type milling machine, a hollow stationary base, a cutter head, means mounting the cutter head on the outer side of the base for vertical movements relative thereto, means for moving the cutter head vertically, a spindle mounted for rotary movement by the cutter head, a motor on the base, a belt drive from the motor to said spindle comprising a shaft in the base, pulleys fixed on said shaft, a belt in the base and

driving one of said pulleys from the motor, a belt extending to the outer side of the base and driving said spindle from another of said pulleys, rigid means comprising a pair of rigid screw threaded parts connecting said shaft and spindle and maintaining them in fixed spaced relation and adapted to impart movement from one to the other, one of said parts exposed for manipulation from the outer side of the base for adjusting the position of said shaft to vary the distance between the centers of the spindle and shaft, and means mounting said shaft in said base for movement by said rigid means to compensate for the shifting of the center of the spindle as the cutter head is moved vertically.

6. In a hand type milling machine, a base, a cutter head, means mounting the cutter head on the base for vertical movements, means for moving the cutter head vertically, a spindle rotatably mounted by the cutter head, a motor on said base, a belt drive from the motor to the spindle comprising a support including spaced upper and lower members, a block on the support between said members, flanges on the block at the side edges of the members and preventing lateral displacement of the block from between the members, a shaft rotatably supported by said block, pulleys fixed on said shaft, a belt driving one of said pulleys from the motor, a belt driving the spindle from another of said pulleys, rigid means connecting the spindle and block and thus maintaining the spindle and shaft in fixed spaced relation and adapted to impart movement from one to the other, and said support mounting said block and thereby the shaft for movement by said rigid means to compensate for the shifting of the center of the spindle as the cutter head is moved vertically.

7. In a hand type milling machine, a base, a cutter head, means mounting the cutter head on one side of the base for vertical movements, means for moving the cutter head vertically, a spindle rotatably mounted by the cutter head, a motor on said base, a belt drive from the motor to the spindle comprising a support including spaced upper and lower members, a block on the support between its members, flanges on the block at the side edges of the members and preventing lateral displacement of the block from between the members, a shaft rotatably supported by the block, pulleys fixed on the shaft, a belt driving one of the pulleys from the motor, a belt driving the spindle from another of said pulleys, rigid means connecting the spindle and block and thus maintaining the spindle and shaft in fixed spaced relation and adapted to impart movement from one to the other, and said support mounting said block and thereby the shaft for horizontal movement by said rigid means toward and from said side of the base to compensate for shifting of the center of the spindle as the cutter head is moved vertically.

8. In a hand type milling machine, a base, a cutter head, means mounting said cutter head on one side of the base for vertical movements, means for moving the cutter head vertically, a spindle rotatably mounted by the cutter head, a motor on the base, a belt drive from the motor to the spindle comprising a shaft, pulleys fixed to said shaft, a belt driving one of said pulleys from the motor, a belt driving the spindle from another of said pulleys, rigid means connecting the shaft and spindle and maintaining them in

5 fixed spaced relation and adapted to impart movement from one to the other, and means mounting said shaft for horizontal movements by said rigid means toward and from said side of the base to compensate for the shifting of the center of the spindle as the cutter head is moved vertically.

9. In a hand type milling machine, a base, a cutter head, means mounting the cutter head on the base for vertical movements, means for imparting vertical movements to the cutter head, a chuck receiving spindle in said head and mounted thereby for rotating movement, a pulley on said spindle, a motor on said base, a block to one side of said spindle, a shaft mounted by said block, means mounting said block for horizontal movement toward and from the plane of movement of said spindle, pulleys on said shaft, a belt drive from the motor to one of the shaft mounted pulleys, a belt drive from another of the shaft mounted pulleys to the spindle mounted pulley, and rigid means connecting the block and cutter head and maintaining them and said shaft and spindle in predetermined spaced relation and serving as vertical movement is imparted to the cutter head to impart horizontal movement to the block.

10. In a hand type milling machine, a base, a cutter head, means mounting the cutter head on the base for vertical movements, means for moving the cutter head vertically, a spindle mounted for rotary movement by the cutter head, a motor on said belt, a belt drive from the motor to the spindle comprising a support including upper and lower members, a block on the support between the members, means preventing lateral displacement of the block from between the members, a shaft rotatably supported by said block, pulleys fixed on the shaft, a belt driving one of the pulleys from the motor, a belt driving the spindle from another of the pulleys, a tubular extension on one end of the block, a means about said extension, means about said spindle and in which the latter turns, a part at right angles to said shaft and secured fast to the means about said tubular extension and having a screw thread, a part turnable in the means about the spindle and at right angles to the latter and threaded to the first mentioned part, means preventing longitudinal movement of the second mentioned part relative to the means about the spindle, said parts adapted to be adjusted on their screw threaded connection to adjust the distance between the spindle and shaft centers, and said support 45 mounting said block and thereby the shaft for movement by said parts to compensate for the shifting of the center of the spindle as the cutter head is moved vertically.

60 NEWMAN M. MARSILIUS.
